UNITED STATES PATENT OFFICE

145,691

DESIGN FOR A LUBRICATING EQUIPMENT CABINET

Arthur M. Fitzpatrick, Jr., Detroit, Mich., assignor to Stewart-Warner Corporation, Chicago, Ill., a corporation of Virginia

Application October 26, 1945, Serial No. 123,217

Term of patent 14 years

(Cl. D52—2)

To all whom it may concern:

Be it known that I, Arthur M. Fitzpatrick, Jr., a citizen of the United States, residing at Detroit, in the county of Wayne and State of Michigan, have invented a new, original, and ornamental Design for a Lubricating Equipment Cabinet, of which the following is a specification, reference being had to the accompanying drawing, forming part thereof.

The figure is a perspective view showing the

front, top, and one side of a lubricating equipment cabinet showing my new design.

The opposite side is of the same appearance as that shown, and the rear is similar to the side, without the central vertical partition line.

I claim:

The ornamental design for a lubricating equipment cabinet, substantially as shown and described.

ARTHUR M. FITZPATRICK, JR.
